UNITED STATES PATENT OFFICE

WILLETT FISHER, OF HOMER, NEW YORK.

BOB-SLED.

SPECIFICATION forming part of Letters Patent No. 336,632, dated February 23, 1886.

Application filed July 31, 1885. Serial No. 173,149. (No model.)

To all whom it may concern:

Be it known that I, WILLETT FISHER, a citizen of the United States, residing at Homer, in the county of Cortland and State of New York, have invented certain new and useful Improvements in Bob-Sleds and Sleighs; and I do hereby declare the following to be a full, clear, and exact description of the invention, such as will enable others skilled in the art to which it appertains to make and use the same, reference being had to the accompanying drawings, which form part of this specification.

My invention relates to an improved means for strengthening and supporting the body of sleds, bob-sleds, and sleighs; and it consists in the detailed construction of the same, herein-after described, and more particularly pointed out in the claims.

In the manufacture of this class of devices heretofore it has been found extremely difficult, in all frame constructions, to furnish a sufficiently durable support between the runner and the beam above, to sustain the load which is usually placed upon them for any considerable length of time. The knee, usually inserted by means of mortises and tenons, however strongly braced, frequently works loose, owing to the rigid construction of the sled and the oftentimes uneven surface over which it is drawn, and requires repair, or from a few months exposure to the weather the moisture which accumulates about the tenons so decays the wood as to necessitate the insertion of a new knee.

In the drawings, Figure 1 is a perspective view showing the side of my improved device as applied to a sled. Fig. 2 is also a perspective view showing the end. Fig. 3 is a sectional view of Fig. 1 on the line X-X, showing the line of connection between the filling-block and the beams; and Fig. 4 is a modified form of the same.

A represents a bob-sled with runners B, constructed, in the usual way, of bent or sawed wood, having metal shoes C thereon, and D the cross-beams on the upper part of the framework. Upon the front and rear sides of the cross-beams I secure supporting-irons E and E', which extend from one runner to the other, and are semicircular in form, by means of bolts

e, which may be fastened by nuts or by riveting. The supporting-irons in their circular shape are made to extend a sufficient distance below the beam to form the knees e' of the sled. A curved or arched filling-block, F, is secured 55 to the under side and at a short distance from the end of the cross-beam, which is made to extend downward and outward to about one-third or one-half the distance from the cross-beam to the runner, and to fit within and between the supporting-irons E and E', to which it is secured by bolts e in the same manner as the cross-beam. At the lower extremity of the curved filling-block F, the depending portion of the supporting-iron E is bent forward 60 and supporting-iron E' is bent backward to form knees e', which brace in opposite directions, and are provided with feet e'', through which they are secured to the runner by means of bolts and nuts or rivets, thus forming a continuous supporting-iron on the front and rear of the cross-beam, which extends to the runner, forming bracing-knees. Through the ends of the cross-beam D a headed bolt or rod, G, is passed, which is secured through the lower 75 end of the filling-block F by means of a nut, g, which serves as a brace to support the beam and to give additional strength to the knees below. These braces also secure the rave H to the ends of the cross-beams, which enables 80 the rave to act as a strengthening-piece between the beams and support the knees against any unusual strain, having a tendency to tilt the beams forward or backward.

Where two of these sleds are used for one 85 conveyance in order to facilitate turning, there is secured on the front sled the ordinary iron circle or fifth-wheel, I, which is attached to the curved cross-supports J and pivotal block K, which rest on and are fastened to the cross-beams D. The front end of the sled or sleigh box is pivotally secured to the block K, to permit of a wide swinging movement in turning the conveyance around.

In Fig. 3 I have shown the filling-block F 95 with a long bevel, f, on its upper curved surface, to enable it to be secured to the cross-beam D by bolts e', or other means, to form a strengthening-brace of itself, while in Fig. 4 I have shown its slightly-beveled end f' adapted 100

to abut against a shoulder of the cross-beam, and to be held in position by the bolts *e* through the supporting-irons *E E'*.

While I may use either of these forms of attachment of the filling-block to the cross-beam, I prefer the form shown in Fig. 3 in the construction of my sled.

I usually make my supporting-irons of wrought-iron, but they may be made of any kind of malleable iron or steel; or, if desired, they may be cast of the form shown, or both irons may be cast in one piece, having a connecting-bar, *e*², on each side, as shown in dotted lines in Fig. 1, and the cross-beam may be fitted 15 in between them, as is also the filling-block.

I am aware that it is not new to construct a sled with curved wooden knees resting on the runner and supporting the cross-beam above, with a metallic plate underneath such knee; 20 nor is it new to attach bracing iron knees to the ends of the cross-beam and to the runner of the sled, but these I do not claim; but

What I do claim, and desire to secure by Letters Patent, is—

25 1. A sled or sleigh having two supporting-irons extending from one runner to the other and attached to the cross-beam on its front and rear sides, the irons having a part of their de-

pendent portions bent forward and backward to form knees, and secured to the runners, as 30 set forth.

2. The combination, with a sled or sleigh having supporting-irons extending across the runners and attached to the cross-beam on its front and rear sides, a part of the depending 35 portion of the irons being bent forward and backward to form knees, of a curved filling-block secured between the depending irons and fastened to the cross-beam, substantially as shown, and for the purpose set forth.

3. The combination, with a sled or sleigh having supporting-irons semicircular in form extending from one runner to the other and secured to the front and rear sides of the cross-beam, and having depending portions bent 45 forward and backward to form bracing-knees, of a curved filling-block secured to the beam and between the supporting-irons, having a brace in its lower portion extending to the outer end of the cross-beam, as set forth.

In testimony whereof I affix my signature in presence of two witnesses.

WILLETT FISHER.
